WINDOW CURTAIN OR SIMILAR ARTICLE

Joseph R. Johnston, Philadelphia, Pa., assignor
to North American Lace Co., Inc., Philadel-
phia, Pa.

Application August 6, 1953, Serial No. 26,300

Term of patent 3½ years

(Cl. D47—6)

To all whom it may concern:

Be it known that I, Joseph R. Johnston, a citizen of the United States of America, residing in Philadelphia, county of Philadelphia, and State of Pennsylvania, have invented a new, original, and ornamental Design for a Window Curtain or Similar Article, of which the following is a specification, reference being had to the accompanying drawing, forming part thereof, wherein the figure is a plan view of a window curtain showing my new design on a dark background so as to bring out the details thereof more clearly.

I claim:

The ornamental design for a window curtain or

similar article, substantially as shown and described.

JOSEPH R. JOHNSTON.
